RADIATOR

Karel Maret, Mahr.-Ostrau, Czechoslovakia, assignor to Société de Dietrich & Cie, Reichshoffen, Bas-Rhin, France

Application November 20, 1933, Serial No. 698,912
In Czechoslovakia November 25, 1932

4 Claims. (Cl. 257—140)

This invention relates to a radiator of sheet metal.

The vessels of the existing types of radiators of sheet metal comprise screw joints or weldings for their uniting. Connection by screwing requires a number of screw members which are quite expensive to produce and which have to be packed relative to one another. Autogenous welding, on the other hand, is costly and bothersome, and in both cases the radiators are of relatively high cost.

It is the object of the invention to reduce this cost of production as much as possible, and this object is attained by rolling the pressed out 15 radiator necks into connecting or spacing rings.

By way of example, the invention is illustrated in the accompanying drawing, which shows two embodiments thereof and in which Figure 1 is a section of a radiator whose members are some distance apart from each other; 20 and Figs. 2 *a* and *b*, sections of radiators whose members are closely adjacent.

Referring to the drawing, the shells 1 of the radiator, which are pressed from thin steel plate 25 or other suitable material, possess a neck 2 pressed out of the radiator top and are united by welding to form a radiator vessel. Inside the top the usual stiffening bush 3 is provided and has passages 4 for the heating medium. In a 30 small radiator group the bush 3 may be dispensed with if the individual tops possess already sufficient stiffness.

The spacing rings 5 for connecting the various vessels are slipped over the pressed out necks 35 2 and connected with these necks and possibly with the stiffening bushes 3 by rolling. For this purpose the spacing rings 5 possess on their inner surface two annular grooves 6 arranged at a distance from one another and adapted to receive both the neck 2 of the radiator top and the stiffening bush 3 which are closely rolled into the grooves by suitable machinery.

The construction according to Figs. 2 *a* and *b* is a simplified form of the one shown in Fig. 1, 45 owing to the use of short connecting rings. For this purpose, each radiator vessel is provided on one side of its top with a connecting neck 2'' having a large diameter and on the other side with a neck 2' of small diameter. When assembling the vessels 1 their necks are telescoped, so that each unit receives with its wide neck 2'' the narrow neck 2' of the adjacent vessel, the diameters of the necks being chosen so that the narrow neck 2' will just fit into the wide 50 neck 2''. The rings 5 inserted between the units possess each an annular groove 6 in which the

two telescoped necks 2' and 2'' are embedded by rolling.

This connection is extraordinarily firm, tight and durable and requires only a narrow connecting ring 5'. Furthermore, only a single groove 5 is required, which means a saving in material and tools.

It is of course possible to provide this narrow ring 5' with two or more adjacent grooves if a single groove should not suffice for packing, though one groove will do as a rule.

If stiffening bushes according to Fig. 1 are to be used, they can be rolled into the annular groove 6 of the connecting ring 5' together with the telescoped necks 2' and 2''.

The free edge of the inner neck of one vessel may be bent at 7 around the bending point of the outer neck of the adjacent vessel to increase the packing tightness of the connection.

Radiators according to the invention can thus 20 be produced very cheaply, the parts being very close to one another and firmly united.

I claim:—

1. A radiator comprising a plurality of sheet metal vessels, a pair of pressed out necks on each vessel, connecting rings surrounding the pressed out necks of adjacent vessels, grooves in the connecting rings and depressions in the necks and fitting in the grooves.

2. A radiator comprising a plurality of sheet metal vessels, a pair of pressed out necks on each vessel, stiffening bushes extending from neck to neck, connecting rings surrounding the pressed out necks of adjacent vessels, grooves in the connecting rings and depressions in the stiffening bushes and necks and fitting in the grooves.

3. A radiator comprising a plurality of sheet metal vessels, a pair of pressed out necks of different diameter on each vessel, the necks of smaller diameter being fitted into the necks of larger diameter of the adjacent vessels, connecting rings surrounding the pressed out necks of larger diameter, grooves in the connecting rings and depressions in the engaging necks and fitting in the grooves.

4. A radiator comprising a plurality of sheet metal vessels, a pair of pressed out necks of different diameter on each vessel the necks of smaller diameter being fitted into the necks of larger diameter of the adjacent vessels, connecting rings surrounding the necks of larger diameter, grooves in the connecting rings, depressions in the necks and fitting in the grooves and bent out portions on the edges of the inner necks.

KAREL MARET.
